UNITED STATES PATENT OFFICE

JAMES WILSON REBER, OF LONDON, ENGLAND

COOLING COKE

Application filed May 21, 1926, Serial No. 110,707, and in Great Britain May 25, 1925.

A known method of cooling coke consists in circulating gases through the hot coke and some form of apparatus for heat recovery, such as a waste-heat boiler. Generally, for 5 the maximum usefulness of the recovery apparatus the heat applied to it should be as constant in temperature as possible and attempts have been made to ensure this constancy.

10 By the present invention this object is attained by keeping a considerable reserve of hot coke above the body of coke through which the gases are circulating, and causing this hot coke to travel into the gas stream at 15 a rate as constant as possible.

For example, any known form of apparatus suitable for cooling coke by the method in question and comprising a shaft-like chamber can be operated according to this 20 invention by providing it with a continuously operating discharging device at bottom, altering the off-take of the circulating gases so that it is at a considerable distance below the level to which the chamber is filled 25 with hot coke, and operating the discharging device at such speed that there is always a quantity of hot coke above the level of the off-take.

Under these conditions the feed of hot 30 coke into the gas current may be kept substantially constant notwithstanding the intermittent charging of coke to the chamber, with the result that the ratio of the volume of gases to that of coke through which they 35 travel remains constant so long as the rate of circulation of the gases is the same. This will tend to ensure a constant temperature of the gases leaving the cooling chamber, with the result (in the case of a waste heat 40 boiler) that a constant quantity of steam per unit time is generated.

The fact that the shaft-like chamber contains a considerable reserve of hot coke 45 makes it worth while to provide the chamber with a water jacket in known manner and to use this jacket for preheating the water fed to the waste heat boiler which is heated by the cooling gases, or to connect the water space of the jacket with that of 50 the waste heat boiler.

In the accompanying drawings, Fig. 1 represents a vertical section through a coke cooling plant constructed according to the invention; Fig. 2 shows a vertical section through a coke cooling chamber according 55 to the invention having a jacket forming a water-space in communication with the waste heat boiler of the plant; Fig. 3 shows a modification of Fig. 2.

In each figure the waste heat boiler, which 60 is indicated diagrammatically, is of the known tubular type.

Referring to Fig. 1 the cooling chamber *a* is constricted at its lower end and has an inclined bottom *b*, at the lower edge of which 65 is a coke discharging device *c* which may be constructed as shown in "The Woodall-Duckham System of Continuous Carbonization in Vertical Retorts" 1923, pages 22-27. This device is rotated on its axis and in conjunction with hangers *d* determines the 70 regular discharge of the coke from the cooling chamber into the receiver *e*. The latter is connected with the cooling chamber in airtight manner and is provided at bottom with a water-sealed door *f* of known kind which 75 is opened periodically to discharge the coke.

An outlet pipe *g* situated at about the middle of the height of the chamber *a* connects the latter with the products inlet chamber *h* of the waste heat boiler *i*, of which the products outlet chamber *h'* is connected with the intake of a fan *k* whose discharge is connected with the receiver *e*. The fan, therefore, circulates the cooling gases through the 80 lower half of chamber *a* and the waste heat boiler *i*.

The chamber *a* is kept substantially full of coke. Its upper part is normally closed by a plate *a'* shown in dotted lines. When, 85 as determined by the rate at which the discharging device *c* is operated, the chamber is ready to receive another charge of coke, the plate *a'* is raised to the position shown in full lines by the approaching telpher carriage *l* which is bringing a skip full of hot coke into position for discharge into the hopper *m* and thence into chamber *a*. The telpher carriage then recedes and the plate *a'* descends to close the chamber. In no case 90 95 100

is the level of the hot coke in chamber *a* allowed to fall to the level of the outlet pipe *g*.

As is known, it is advisable to substitute continuously or intermittently, for a portion of the circulating gases, a like portion of air to ensure combustion of any combustible gas which may be generated in the cooling chamber. In the construction shown in Fig. 1 this air is drawn through a valve *g'* into pipe *g*, so that the combustible gases are burnt in the waste heat boiler, and the corresponding volume of gases is expelled through valve *h²* on the discharge side of the fan *k*.

In Figs. 2 and 3 the parts already described have the same letters as those already used.

In Fig. 2, the water in the water jacket *v* is circulated by a pump *n* through a worm *c* in the feed water tank *p* of the waste heat boiler *i*. The tank *p* has an automatic feed *g*.

In Fig. 3 the upper part *r* of the jacket *v* constitutes the steam space of the waste heat boiler *i*, the lower part or water space of the jacket being connected as shown by pipes *s* and *t* with the water space of the boiler *i*.

Alternatively, the pipe *t* may be omitted and both the space *r* and the boiler *i* connected with a steam drum *u*, as shown in dotted lines.

Having thus described the nature of the said invention and the best means I know of carrying the same into practical effect, I claim:—

A process of cooling hot coke, comprising forming the hot coke into a substantially vertical column, continuously withdrawing coke from the lower part of the column and thereby causing the coke to continuously move downwardly, passing a stream of cooling gases chemically inert towards hot coke into the lower part of the column to cause said gases to traverse the column longitudinally and in counter-current to the moving coke, withdrawing the gases from the column at a point a substantial distance below the upper end of the column, feeding hot coke to the upper end of the column so as to maintain a substantial mass of hot coke above the portion of the column traversed by the gases, extracting heat from the gases withdrawn from the column, and returning the withdrawn gases to the lower part of the column for re-use in the process.

In testimony whereof I have signed my name to this specification.

JAMES WILSON REBER.
